UNITED STATES PATENT OFFICE.

PETER DILLON, OF LAWRENCE, MASSACHUSETTS, ASSIGNOR OF ONE-HALF
TO HENRY C. KING, OF SAME PLACE.

PAPER-CUTTER.

SPECIFICATION forming part of Letters Patent No. 608,549, dated August 2, 1898.

Application filed June 9, 1897. Serial No. 639,967. (No model.)

To all whom it may concern:

Be it known that I, PETER DILLON, of Lawrence, county of Essex, State of Massachusetts, have invented an Improvement in Paper-Cutters, of which the following description, in connection with the accompanying drawings, is a specification, like letters on the drawings representing like parts.

My present invention is an improvement in paper-cutters, having for its object the provision of means to accurately regulate the length of sheets cut, or, in other words, to regulate with absolute definiteness the frequency with which the cutter operates, and also to vary the rate of feed of the paper, a further object of my invention being to greatly increase the range of the machine above that ordinarily possible in paper-cutters.

It is ordinarily the custom in paper-cutting to feed a number of sheets or webs of paper simultaneously, ten or more superimposed sheets being often fed through the cutter, and therefore it becomes highly desirable that there should be as little waste as possible, for the reason that each time a false cut is made or a sheet is cut of the wrong length not only is one sheet spoiled, but the ten or more sheets which are being fed together are all

spoiled. As at present constructed, however, the means for ascertaining the precise adjustment of the machine necessary is crude and imperfect, depending largely upon trial and experiment. Accordingly I have devised a perfected mechanism which not only prevents any accidental slip or uncertainty of movement of the parts, but accurately indicates the precise adjustment necessary for a given cut; also, in the different kinds of

speed-changers at present found in paper-cutters there is always more or less uncertainty of movement, especially when a number of thicknesses of paper are being cut together, more or less slip of the parts being produced, such slip, of course, destroying the accuracy of relative movement which must exist with absolute uniformity between the feeding of the paper and the cutting thereof.

My invention aims at removing all the difficulties above alluded to. Various other details of improvement and advantages thereof

will be more fully pointed out in the course of the following description, reference being had to the accompanying drawings, forming a part of this specification, and the invention will be hereinafter defined in the claims at the end of the specification.

In the drawings, Figure 1 is a rear elevation of the preferred embodiment of my improved paper-cutter, showing clearly the speed-changing and feed-regulating improvements forming a leading part of my present invention, looking toward the left, Fig. 2. Fig. 2 is an end elevation thereof. Fig. 3 is a rear elevation of the speed-changers for the cutting-blades, showing also in broken detail my improved gage. Fig. 4 is a vertical cross-section taken on the line 4 4, Fig. 3. Fig. 5 is a vertical cross-section taken on line 5 5, Fig. 1.

Mounted in suitable end standards A A and cross-braces and framework B are the usual feed-rolls C, cutter-cylinder D, provided with one or more cutting-blades d, coöperating with a fixed blade d', and gears c d', all as usually found in paper-cutters. Suitably journaled in the frame is a shaft E, on which is mounted a cone-pulley E', coöperating with an oppositely-placed cone-pulley E², carried by a shaft E³.

Various kinds of speed-changers have been proposed and used for paper-cutters; but so far as I am aware no mechanism has been provided which would at the same time permit of delicate and accurate adjustment and also be certain in operation, the best of them being very liable to slip, and thereby ruin one or more cuts of the paper.

Accordingly I have provided the cone-pulleys, as above described, on which a belt E⁴ is mounted in usual manner, and have arranged a combined belt shifter and tightener E⁵, (shown in detail in Figs. 3 and 4,) comprising a lever pivotally mounted at its middle portion on a threaded shifting rod e and carrying at its upper end a friction-roll e', between projecting ears e², which embrace the belt between them, as clearly seen in Figs. 2 and 4, and a rigid laterally-projecting rod e³ at its lower end, on which is adjustably mounted a tension weight or device e⁴, so that the pressure of the lever E⁵ against the

belt may be definitely regulated to correspond to the weight of paper being fed through the machine simply by adjusting the tension thereof by moving the weight e^1 one way or 5 the other on the rod e^3 .

By reason of the mechanism just described the belt is never permitted to slacken, but is always maintained uniformly under the same frictional resistance on its pulleys.

10 The pulleys E' E^2 are those employed for regulating the speed of the rotation of the cutter D , being geared therewith through the train of gears shown in Fig. 2 at e^5 e^6 e^7 e^8 , the latter gear meshing with the gear- 15 wheel d^2 .

In the simplest form of machine the shaft E will be the driving-shaft of the machine, having fast and loose pulleys E^6 E^7 at one end thereof, as indicated in dotted lines, Fig. 20 1, it being understood that in machines of this class as commonly constructed the feeding of the paper by the roller C is uniform and unchanged no matter what grade of paper or how many thicknesses thereof 25 are being fed, it being the rule in such machines to change the speed of the cutter only, the same amount of paper always passing thereunder in a given time.

However, it is frequently desirable to be 30 able to change the rate of feed of the paper. For instance, in the case of light paper and few thicknesses thereof it is perfectly practical to cut it more rapidly than in the case of heavy weight and many thicknesses, and 35 accordingly I have herein shown the driving-shaft of the machine at F with fast and loose pulleys F' F^2 , the shaft F having a cone-pulley F^3 connected by means of a belt F^4 to a cone-pulley F^8 , fast on the shaft E , a belt 40 shifter and tightener G being provided to keep the parts from slipping and to shift the belt, being operated by a screw-rod g and hand-wheel g' . (See Figs. 1 and 5.) If preferred, the belt tightener and shifter E^5 may 45 be substituted for the one marked G .

By reason of this construction it is evident that simply by turning the hand-wheel g' one way or the other the speed of the shaft E , and therefore of the feeding-roll C 50 through the gears c and e^9 , may be varied as desired, and this may be accomplished either with or without increasing the speed of the cutting-cylinder D simply by shifting the hand-wheel e^8 of the main shifting rod e at 55 the same time that the belt F^4 is shifted.

Referring to Fig. 3, it will be seen that the rod e is provided with one set of threads to shift the belt and with another set of threads e^{10} of finer pitch, on which is mounted the indicator e^{12} , shown in side elevation in Fig. 4, where it will be seen that it rests on an inclined plate e^{13} , graduated as a gage, (see Fig. 3,) the indicator projecting below the rod e and having a socket e^{14} , containing a spring 65 e^{15} , bearing against the beam B , so as to hold the indicator in free sliding engagement with the plate e^{13} . This construction permits the

operator to determine with the utmost accuracy precisely how far the belt must be shifted in order to cut a given length of paper.

70 A further important feature of my invention remains to be described, and consists in providing mechanism whereby the range of relative rates of feed and cut may be greatly increased in the same machine without the necessity of dismembering the machine in any way or requiring any particular skill in order to adjust the parts. The mechanism for this purpose comprises a quadrant or shifting plate G' , pivoted at g^8 and capable of being swung up or down to a limited extent by the handle g^{10} and cam-clamp g^2 , operating in a slot g^3 , (see Fig. 2,) to securely clamp the angle bracket or quadrant G firmly against the frame of the machine, so 75 as to prevent any vibration or looseness thereof, and a spring-pin g^4 , serving to engage a series of holes g^5 , properly fixes the bracket G in its adjustment. By this means the gear-pinion e^6 may be raised or lowered to 80 mesh with either one of a series of different-sized gears e^5 e^{16} e^{17} , (see Fig. 1,) these gears being splined on the shaft e^3 and freely movable longitudinally thereof, said gears having side flanges e^{18} , as clearly shown in Fig. 1, to 85 prevent their getting out of mesh with the gear e^6 when the machine is running.

The provision just described permits a certain range of adjustment corresponding to the length of the cone-pulleys e^1 e^2 for the 90 gear e^5 , for instance, and then the shaft being shifted back to its original position and the gear e^{16} being brought into mesh with the gear e^6 a further adjustment of the cutting mechanism is rendered possible similar in extent 95 to that before accomplished, but in addition thereto, and so likewise the belt being again shifted back to its original position and the gear e^{17} being brought into mesh with the gear e^6 a further increase of adjustment is 100 accomplished, and all this is done without any inconvenience and delay.

I have herein described the preferred embodiments of my invention; but I am aware that many and various changes may be resorted to both in the details of construction and in the combinations thereof without in any way departing from the spirit and scope of my invention, and therefore I do not intend to limit myself to the precise construction herein shown and described.

Having described my invention, what I claim as new, and desire to secure by Letters Patent, is—

1. In a paper-cutter, the combination with 125 feeding mechanism for the paper, cutting mechanism, and a main driving-shaft having unvarying speed, of means permanently mounted and journaled in the organized machine to vary at will the speed of said cutting 130 mechanism, and of said feeding mechanism independently of each other, substantially as described.

2. A paper-cutter, having in combination,

feeding mechanism adapted to receive and feed a plurality of superimposed thicknesses of paper of different weights or grades, severing devices to which said thicknesses of paper are simultaneously fed to be cut, and operating mechanism, including an intermediate cone-and-belt device, for driving said severing devices and feeding mechanism with relative speeds required for producing the uniform lengths of sheets desired, said operating mechanism including means to accurately change the frictional engagement of said belt as, and according to, the different resistances offered by the different thicknesses and different weights or grades of paper being cut, and means to vary the relative speed of the severing devices for cutting sheets of different lengths, substantially as described.

3. The combination in a paper-cutter, with the feed-rolls for feeding the paper, and severing devices for cutting the paper of a cone-and-belt speed-changer geared between and with said feed-rolls and severing devices, and means to maintain friction in said cone-and-belt device varying in proportion to the varying loads, a second cone-and-belt speed-changer mounted adjacent and driving said first-mentioned cone-and-belt mechanism, whereby the speed of said severing devices and of said feed-rolls may be varied at will either together or independently of each other as desired, substantially as described.

4. A paper-cutter having, in combination, paper-severing mechanism, feed-rolls to feed the paper thereto, and a pair of coöperating cone-pulleys between said feeding and severing mechanisms and driving the latter, a belt passed about said cone-pulleys, a pivoted lever having a friction-roll at one end between two ears, said ears embracing said belt, and said roll resting against the latter, and at its other end having a laterally-projecting rod on which is mounted a weight, and means to adjust said weight on said rod, whereby the tension of said belt may be varied according to the paper being fed and cut by the machine, substantially as described.

5. The combination, in a paper-cutter, with the paper-severing devices, feed-rolls to deliver the paper thereto, and driving mechanism for said parts, said driving mechanism including a power-shaft and gear driven thereby, of a shifting plate mounted on the frame of the machine and carrying a train of gear-wheels, said train meshing at one end with the said driven gear, said train and said driven gear being one provided with a plurality of different-sized gear-wheels, and the other being adapted to mesh with any one of said different-sized gear-wheels, and one being freely movable laterally relatively to the other, said train meshing at its opposite end with the mechanism driven thereby for operating said paper-severing devices, and means to move said plate concentrically with the gear-wheel at said last-mentioned end of said train, in or-

der to operate the train through any one of said different-sized gear-wheels, substantially as described.

6. The combination in a paper-cutter, with the feeding mechanism for feeding the paper, and severing devices for cutting the paper, of operating mechanism geared between and with said feeding mechanism and severing devices, said operating mechanism including a main driving-shaft, a cone-and-belt speed-changer, and gear driven thereby, means to maintain friction in said cone-and-belt device varying in proportion to the varying amounts or kinds of paper being fed, a shifting plate mounted on the frame of the machine and carrying a train of gear-wheels, said train meshing at one end with the said driven gear, said train and said driven gear being one permanently provided with a plurality of different-sized gear-wheels, and the other being adapted to mesh with any one of said different-sized gear-wheels and one being freely movable laterally relatively to the other, said train meshing at its opposite end with the mechanism driven thereby, and means for moving said plate concentrically with the gear-wheel at said last-mentioned end of said train, substantially as described.

7. The combination, in a paper-cutter, with the paper-severing devices, feed-rolls to deliver the paper thereto, and driving mechanism for said parts, said driving mechanism including a power-shaft and gear driven thereby, of a shifting plate mounted on the frame of the machine and carrying a train of gear-wheels, said train meshing at one end with the said driven gear, said train and said driven gear being one provided with a plurality of different-sized gear-wheels, and the other being adapted to mesh with any one of said different-sized gear-wheels, and one being freely movable laterally relatively to the other, and one having side flanges ^{e18} to prevent accidental shifting out of mesh, said train meshing at its opposite end with the mechanism driven thereby, and means to move said plate concentrically with the gear-wheel at said last-mentioned end of said train, in order to operate the train through any one of said different-sized gear-wheels, substantially as described.

8. The combination, in a paper-cutter, with feed-rolls to feed the paper, and severing devices to cut the paper, of a frictional speed-changer capable of a long range of delicate variations, means to vary said friction in proportion to the varying resistance of the paper fed, said friction being maintained always sufficient to prevent slip, said speed-changer comprising a pair of coöperating cone-pulleys, a belt passed about them, a combined belt shifter and tightener in engagement with said belt, an adjustable tension device thereon to vary the frictional engagement thereof with the belt, a threaded shifting rod on which said shifter and tightener is mounted, said rod extending in the organ-

ized machine parallel to said pulleys and having a portion thereof, beyond the range of movement of said shifter and tightener, provided with finer threads than the shifting-
5 threads thereof, an indicator mounted on said fine-threaded portion, and a gage fixed on the machine and over which said indicator is caused to travel by the fine threads, whereby an indicator is provided within the
10 compass of the machine for and in connec-

tion with a long range of movement of said shifter and tightener, substantially as described.

In testimony whereof I have signed my name to this specification in the presence of 15 two subscribing witnesses.

PETER DILLON.
